UNITED STATES PATENT OFFICE.

DENNIS L. CUMMINGS, OF BOSTON, MASSACHUSETTS.

FLUSH INSERT FOR CONCRETE WORK.

1,244,034.

Specification of Letters Patent. Patented Oct. 23, 1917.

Application filed April 12, 1917. Serial No. 161,465.

To all whom it may concern:

Be it known that I, DENNIS L. CUMMINGS, a citizen of the United States, residing at Boston, county of Suffolk, State of Massachusetts, have invented an Improvement in Flush Inserts for Concrete Work, of which the following description, in connection with the accompanying drawing, is a specification, like characters on the drawing representing like parts.

This invention relates to flush inserts for concrete work such as are used to provide in the concrete a suitable anchorage to which beams, fixtures, etc., may be attached.

15 The object of the invention is to provide a novel flush insert of this type which is simple and inexpensive to manufacture and which makes a firm anchorage for the part to be supported.

20 In order to give an understanding of the invention, I have illustrated in the drawings a selected embodiment thereof which will now be described, after which the novel features will be pointed out in the appended 25 claims.

In the drawings, Figure 1 is a sectional view on the line 1—1, Fig. 2;

Fig. 2 is a sectional view on the line 2—2, Fig. 1;

30 Fig. 3 is a perspective view of a device embodying my invention.

My improved insert comprises a box-like element 1 which may have various shapes provided it is open at one side, as shown at 35 2. In the illustrated embodiment of the invention the box-like element 1 comprises the two sides 3 and the top 4 which is arcuate in shape. The box is provided with the laterally-extending flanges 5 at the ends 40 thereof and also with the flanges 6 which extend laterally from the sides 3. Each side 3 is notched, as shown at 7 to receive an anchoring member 8 which is herein shown as in the form of a rod or heavy wire. This 45 anchoring member 8 is bent into a U-shape and when in operative position the bridge portion 9 thereof extends through the notches 8 and across the open side 2 of the box-like element 1, and the sides or legs 10 50 thereof extend parallel to the sides 3 of the box-like element and are situated on the out-

side thereof. The extremities 11 and 12 of the legs are bent laterally and preferably in opposite directions.

In using the device it is placed on the concrete form 13 with the flanges 5 and 6 resting against the form, the insert being placed at the point where some anchorage in the finished concrete structure is desired. When the concrete is poured it flows around the 60 insert and incloses the latter and the legs 10 with their offset portions 11 and 12 become embedded in the concrete. When the concrete has set the insert is firmly anchored therein because of the shape of the offset 65 portions 10 and 11 of the anchoring member. When the form is removed, a hollow or recess is presented in the face of the concrete due to the presence of the box-like element 1, and this recess has the portion 9 of 70 the anchoring member extending transversely thereacross. This portion 9 provides a support to which different objects can be secured. It will be noted that in my device the anchoring member serves not only as the 75 support to which attachment may be made, but by reason of its construction it constitutes the means for anchoring the support in the concrete. The device is simple and inexpensive to make and is easily used and is 80 effective in operation.

I claim:

1. An insert for concrete work comprising a box-like element having an open side which is adapted to be placed against the 85 form used for said concrete work, the opposite sides of said element having notches therein on their edges, and a U-shaped anchoring member having its bridge portion extending through said notches and across 90 the open side of the box-like element and its legs extending parallel to said sides and provided with means for anchoring said member in the concrete, said member and boxlike element being separable for shipment and adapted for assembling as the device is put into place.

2. An insert for concrete work comprising a box-like element having an open side which is adapted to be placed against the 100 form used for said concrete work, the opposite sides of said element having notches

therein on their edges, and a U-shaped anchoring member having its bridge portion extending through said notches and across the open side of the box-like element and its 5 legs extending parallel to said sides, the ends of said legs being bent laterally to provide means for anchoring said member in

the concrete, said member and boxlike element being separable for shipment and adapted for assembling as the device is put 10 into place.

In testimony whereof, I have signed my name to this specification.

DENNIS L. CUMMINGS.
